UNITED STATES PATENT OFFICE

146,812

DESIGN FOR A HAND LUGGAGE CASE

Clifford Brooks Stevens, Milwaukee, Wis., assignor to Wheary Incorporated, Racine, Wis., a corporation of Wisconsin

Application April 12, 1946, Serial No. 128,535

Term of patent 7 years

(Cl. D87—5)

To all whom it may concern:

Be it known that I, Clifford Brooks Stevens, a citizen of the United States, residing at Milwaukee, in the county of Milwaukee and State of Wisconsin, have invented a new, original, and ornamental Design for a Hand Luggage Case, of which the following is a specification, reference being had to the accompanying drawing, forming part thereof.

The single figure is a perspective view of a hand luggage case showing my new design.

The side and end of the case not shown are identical in appearance with those illustrated. The bottom of the case is plain.

The design for the luggage case disclosed is characterized by the apron portion at the top having the configuration and arrangement shown.

I claim:

The ornamental design for a hand luggage case, as shown and described.

CLIFFORD BROOKS STEVENS.
